CONVERSION OF HYDROCARBON OILS

Percy Mather, Chicago, Ill., assignor to Universal
Oil Products Company, Chicago, Ill., a corpora-
tion of Delaware

Application October 20, 1938, Serial No. 235,938

8 Claims. (Cl. 196—49)

The invention particularly refers to a novel and advantageous process for the extensive distillation and reduction of residual liquids resulting from the pyrolytic conversion of hydrocarbon oils to a heavier residual product, accompanied by the production from said cracked residue of high yields of lighter and more desirable oil suitable, for example, as premium fuel.

While the features of the invention are applicable to the treatment of practically any heavy residual oil, they are particularly advantageous as applied to the treatment of residual oils resulting from cracking and the residuum distilling and reducing system may be operated in conjunction with practically any type of cracking unit wherein heavy liquid residue is produced.

From the following more detailed description of the process, its advantages will be readily apparent to those familiar with the art. It offers a means of recovering high yields of more valuable products from cracked residues without resorting to coking and without the deleterious degree of destructive distillation which is common to coking operations and results in high gas losses and reduced yields of valuable light liquid products.

In the preferred embodiment of the invention, the residual liquid conversion products, which result from the cracking of lighter hydrocarbon oils at substantial super-atmospheric pressure, are reduced, by two sequential stages of flash distillation and without additional heating, to a heavier liquid residue which is then quickly heated to cracking temperature without allowing deleterious secondary cracking reactions to occur and the resulting highly heated products are quickly separated at sub-atmospheric pressure and/or in the presence of light vapors which exert a partial pressure effect, leaving a final residual product which is normally solid or semi-solid at atmospheric conditions but which, due to the high temperature prevailing in the last mentioned vaporizing and separating step, may be quickly and continuously removed therefrom in liquid state and recovered. Preferably, the vaporous products evolved from the cracked residue in both the primary and secondary flashing steps or, more particularly, the components of these vapors which boil above the range of the desired final light distillate (gasoline) product of the process, are condensed and returned to the cracking system wherein said liquid residue is produced or to a separate cracking system for further cracking treatment, to produce therefrom additional yields of valuable light distillate

such as gasoline. The vapors evolved in the cracking and reduced pressure vaporizing step, to which the flashed residue is supplied, are condensed and recovered as a final product of the process and, due to the treatment afforded the flashed residue in accordance with the provisions of the invention, the yields of this product will often exceed 50% by weight of the flashed residue. It will consist essentially of an oil of materially lower boiling characteristics than the flashed residue and its characteristics may be controlled to meet market requirements for premium fuel oil.

The accompanying diagrammatic drawing illustrates one specific form of apparatus embodying the features of the invention and in which the process of the invention may be conducted. In this illustration, the residue-reducing steps are interconnected and conjointly operated with a relatively simple form of single coil cracking system, but it will be evident, as previously stated, that the novel features provided by the invention may be advantageously employed in conjunction with other types and other specific forms of cracking systems.

Referring to the drawing, heating coil 1 is disposed within a furnace 2 and the oil supplied to this coil, in the manner which will be later described, is heated therein to the desired cracking temperature, preferably at a substantial super-atmospheric pressure by means of heat derived from the furnace. The resulting heated products are discharged from coil 1 through line 3 and valve 4 into reaction chamber 5 wherein their cracking treatment continues at a superatmospheric pressure which may be substantially the same or somewhat lower than that employed at the outlet of coil 1, chamber 5 being preferably insulated to conserve heat, although insulation is not indicated in the drawing.

Both vaporous and liquid conversion products are withdrawn, in the case here illustrated, from the lower portion of chamber 5 in commingled state and are directed through line 6 and valve 7 to vaporizing and separating chamber 8 which comprises the first flash distilling zone of the system and is operated at a substantially reduced pressure relative to that employed in chamber 5. The vapors evolved from the liquid conversion products in chamber 8 and the vaporous products supplied to this zone from chamber 5 are directed from the upper portion of chamber 8 through line 9 and valve 10 to fractionation in fractionator 11.

In fractionator 11, the components of the

vaporous products supplied to this zone which boil above the range of the desired final light distillate products of the process are condensed therein as reflux condensate. In this particular case, the total reflux condensate formed in fractionator 11, with the exception of a relatively small amount of selected low-boiling fractions which are separately removed therefrom and utilized, as will be later described, is directed from the lower portion of the fractionator through line 12 and valve 13 to pump 14 by means of which it is supplied through line 16 and valve 17 to cracking treatment, as previously described, in heating coil 1. It is, however, entirely within the scope of the invention to employ a cracking system utilizing a plurality of heating coils and, in such cases, the reflux condensate may, when desired, be separated by its fractional condensation in fractionator 11 into selected relatively low-boiling and high-boiling fractions which are subjected in separate heating coils of the system to independently controlled cracking conditions.

Fractionated vapors of the desired end-boiling point and consisting, in this particular case, of vapors boiling within the range of the desired gasoline product and gases, are directed from the upper portion of fractionator 11 through line 18 and valve 19 to condenser 20 wherein they are subjected to condensation and cooling. The resulting distillate and uncondensed gases are directed from condenser 20 through line 21 and valve 22 to collection and separation in receiver 23. The gases which remain uncondensed and undissolved in the distillate in receiver 23 are released therefrom through line 24 and valve 25 to storage or elsewhere, as desired. Distillate collected in receiver 23 is withdrawn therefrom through line 26 and valve 27 to storage or to any desired further treatment. Regulated quantities of the distillate collected in receiver 23 may, when desired, be returned by means of line 28, valve 29, pump 30, line 31 and valve 32 to the upper portion of fractionator 11 to serve as a refluxing and cooling medium in this zone.

The liquid residue resulting from flash distillation of the liquid conversion products in chamber 8 is withdrawn from the lower portion of this zone through line 33 and a regulated portion thereof may, when desired, be directed to cooling and storage through line 34 and valve 35 and recovered as a final product of the process. However, at least a substantial portion of this flashed residue is directed through valve 36 in line 33 to a secondary vaporizing or flash distilling chamber 37 which is operated at a substantially reduced pressure relative to that employed in chamber 8 and wherein the primary flashed residue is substantially further vaporized.

The vapors which are evolved and remain uncondensed in chamber 37 are directed from the upper portion of this zone through line 38 and valve 39 to dephlegmator 40 wherein a rough separation of their relatively light and relatively heavy components is accomplished by fractional condensation. Dephlegmator 40 also serves in this particular case as a zone to which hydrocarbon oil charging stock for the process is supplied and wherein it is preheated by direct contact with the relatively hot vapors from chamber 37 and serves as a refluxing and cooling medium for the vapors. The charging stock, which is preferably an oil of high-boiling characteristics or relatively wide boiling range, although it may be any desired type of oil, is supplied through line 41 and valve 42 to pump 43 by means of

which it is fed through line 44 and valve 45 into dephlegmator 40.

The relatively heavy components of the vapors supplied to dephlegmator 40 which are condensed as reflux condensate in this zone and the preheated charging stock, or the components thereof which remain unvaporized in dephlegmator 40, are directed from the lower portion of this zone through line 46 and valve 47 to pump 48 by means of which this material is supplied through line 49, valve 50, line 51 and valve 52 to fractionator 11. The oil thus supplied from dephlegmator 40 to fractionator 11 is directly commingled in the latter zone with the relatively hot vapors undergoing fractionation therein, serves as a cooling and refluxing medium for assisting fractionation of the vapors and the components of this oil which remain unvaporized in fractionator 11 commingle with the reflux condensate formed therein and are directed therewith, in the manner previously described, to cracking treatment in heating coil 1. This oil may contain an appreciable quantity of components boiling within the range of the desired light distillate product of the process. In such cases, these desirable low-boiling components will be included with the stream of fractionated vapors removed from the upper portion of fractionator 11 and will be recovered with the rest of the light distillate product in receiver 23.

When the oil withdrawn from the lower portion of dephlegmator 40 and/or the reflux condensate formed in this zone contains any substantial quantity of low-boiling fractions, which are undesired as components of the final light distillate product collected in receiver 23, this oil instead of being supplied to fractionator 11, as illustrated, may be supplied by well known means, not shown, directly to coil 1 or to a separate cracking coil of the system, in case a multiple coil cracking system is employed.

The low-boiling components of the vapors from chamber 37, which remain uncondensed in dephlegmator 40, and the low-boiling components of the charging stock supplied to this zone, which are vaporized and are not recondensed therein, are directed from the upper portion of the dephlegmator through line 53 and valve 54 to condensation and cooling in condenser 55 wherefrom the resulting distillate and any uncondensed gases are directed through line 56 and valve 57 to collection and separation in receiver 58.

The gases which remain uncondensed and undissolved in the distillate collected in receiver 58 are released from this zone through line 59 and valve 60 to storage or elsewhere, as desired. All or a portion of the distillate collected in receiver 58 may, when desired, be recovered as a final product of the process, by well known means not illustrated, or it may be directed, all or in part, from receiver 58 through line 61 and valve 62 to pump 63 by means of which it is fed through line 64 wherefrom it may be supplied, all or in part, through line 65, valve 66, line 51 and valve 52 to fractionator 11, to serve as a cooling and refluxing medium in this zone and therein undergo the same fractionating treatment afforded the other materials supplied thereto. Also, regulated quantities of the distillate collected in receiver 58 may, when desired, be returned through valve 67 in line 64 to the upper portion of chamber 37 to commingle therein with the vapors evolved in this zone and serve as a cooling and refluxing medium thereby assisting the desired

separation of vapors and non-vaporous residue in this zone.

The invention also contemplates the use of a cooling and refluxing medium in the upper portion of chamber 8 to assist the desired separation of vapors and non-vaporous residue in this zone. Line 68 and valve 69 is provided for the purpose of introducing a cooling oil into the upper portion of chamber 8 and this material may comprise, for example, regulated quantities of the distillate collected in receiver 58 or regulated quantities of all or selected fractions of the condensate formed in fractionator 11 or in dephlegmator 40, although well known means for supplying any of these various materials or any combination thereof to line 68 are omitted from the drawing for the sake of eliminating details which will be readily apparent without illustration.

When the charging stock supplied to dephlegmator 40 contains low-boiling fractions undesired as components of the light distillate product collected in receiver 23, such as, for example, gasoline or gasoline fractions of inferior antiknock value, fractionation of the charging stock is preferably so controlled in dephlegmator 40 that substantially all of these undesired low-boiling fractions are included in the overhead vaporous stream removed from this zone. In such cases the distillate collected in receiver 58 is preferably not supplied to fractionator 11, but may be supplied, when desired, by well known means not illustrated, directly to coil 1 or to a separate cracking coil of the system, in case a multiple coil cracking system is employed.

Due to the extensive vaporization afforded the cracked residue in chambers 8 and 37, the heavy residual liquid product which remains unvaporized in the latter zone will be substantially free of low-boiling components desirable as cracking stock for heating coil 1 and, except for the advantageous further treatment to which this material is subjected, in accordance with the provisions of the invention, it would ordinarily be suitable only as coking stock for producing high yields of coke, minor yields of lower boiling liquid products and substantial quantities of gas. In accordance with the features of the invention, however, this heavy flashed residue is subjected to controlled further cracking treatment and thereby converted into major yields of lighter and more valuable liquid, minor yields of a pitch-like or semi-solid residue, low yields of gas and no substantial quantity of coke. To accomplish this, the heavy flashed residue is directed from the lower portion of chamber 37 through line 70 and valve 71 to pump 72 by means of which it is fed through line 73, valve 74 and line 75 to heating coil 76.

Coil 76 is located within a furnace 77 and, although illustrated in a conventional manner in the drawing, coil 76 and furnace 77 preferably comprise one of several well known types of heaters employing relatively high rates of heating and high oil velocities through the coil, so that the flashed residue may be quickly heated to the desired cracking temperature in coil 76 and discharged therefrom through line 78 and valve 79 into chamber 80 before deleterious secondary cracking reactions, which result in the formation of coke and excessive yields of gas, can occur.

Preferably, in order to increase the velocity of flow through coil 76 and decrease the time during which the flashed residue is maintained at an active cracking temperature in this zone, a

regulated quantity of relatively light distillate is supplied to this zone with the flashed residue. This light distillate is preferably an oil which is not readily cracked to produce coke and gas and may be derived from any external source or from within the system. In the particular case here illustrated, the low-boiling oil supplied to coil 76 comprises a selected low-boiling fraction of the reflux condensate formed in fractionator 11 and consisting essentially of what is commonly termed "pressure distillate bottoms." This material is removed as a sidestream from the upper portion of fractionator 11 and directed through line 81, valve 82, and pump 83 by means of which it is supplied through line 84, valve 85 and line 75 to the inlet of heating coil 76.

When light distillate is supplied, as previously described, to coil 76, its substantially complete vaporization in chamber 80 will exert a partial pressure effect on the products of the flashed residue cracking operation which would otherwise remain unvaporized in this zone. The invention also contemplates the use of sub-atmospheric pressure, when desired, in chamber 80 to assist vaporization and prevent substantial cracking therein. Due to the low effective pressure maintained in chamber 80, cracking of the flashed residue supplied to coil 76 will be substantially limited to that which takes place in the latter zone and may be quite accurately regulated by proper design of the heater for the capacity desired and by control of the rates of heating and oil velocity in the coil. By proper regulation of the control factors mentioned, the flashed residue may be cracked to such a degree in coil 76 and the products vaporized to such a degree in chamber 80 that high yields of lighter and more valuable liquid products are produced without excessive gas formation and without the production of any substantial quantity of coke, leaving a nonvaporous residue which, although normally solid or semi-solid under atmospheric conditions, may be continuously and quickly removed in liquid state from chamber 80 due to the temperature prevailing in this zone. This product is preferably withdrawn from the lower portion of chamber 80 without permitting any substantial body thereof to accumulate in this zone and is directed through line 86 and valve 87 to pump 88 by means of which it is discharged from the system to cooling and storage or elsewhere, as desired, through line 89 and valve 90.

Since chamber 80 functions as a zone wherein a high degree of vaporization is required and since for best results substantially all of the evolved vapors should be separated from the non-vaporous residue in this zone and separately removed therefrom, it is highly desirable to avoid any substantial cooling and fractionation of the evolved vapors in chamber 80, since this would result in appreciable recondensation of the vapors and blending of the resulting condensate with the non-vaporous residue, thus including in the latter relatively low-boiling fractions which are more desirable as components of the overhead condensate. In view of this, I preferably avoid the use of a cooling and refluxing medium in the upper portion of chamber 80. However, the vapors evolved in this zone will ordinarily contain appreciable quantities of entrained or dissolved heavy tar-like and pitchy materials which would be deleterious as components of the final fuel oil product and for best results must be excluded from the overhead stream of vapors removed from the chamber 80.

To accomplish the separation of such deleterious materials from the relatively clean vapors, I preferably provide suitable and well known contacting means such as baffles, perforated pans, bubble trays or the like, not illustrated, in the upper portion of chamber 80, remove a relatively hot condensate from one of the lower trays or decks and return the same in regulated quantities and without intentional cooling to a point in chamber 86 above that from which it is removed. In this manner, I provide a relatively hot washing liquid for the vapors and accomplish removal of the deleterious materials therefrom without substantial cooling and reflux condensation. In the case here illustrated, heavy condensate is directed from a suitable point in chamber 80 through line 105 and valve 106 to pump 107 wherefrom it is returned through line 108 and valve 109 to a higher point in chamber 80. Since the closed cycle is thus established, through which heavy condensate is continuously circulated, any required amount of washing liquid may be provided by controlling the speed of pump 107. However, prolonged continuous circulation of this material will reduce its efficiency since the deleterious heavy materials, which it removes from the vapors, will accumulate therein. I, therefore, provide for continuously or intermittently bleeding off a portion of the washing liquid and removing the same from the system. Line 110, controlled by valve 111, is provided for this purpose, in the case here illustrated, and the relatively heavy and dirty liquid, thus removed from the system, may be discharged through line 110 and valve 111 to cooling and separate storage or it may, when desired, be blended, by well known means not illustrated, with the residual product removed from the lower portion of chamber 80.

The resulting, relatively clean vapors are directed from the upper portion of chamber 80 through line 91 and valve 92 to condensation and cooling in condenser 93 and the resulting condensate and uncondensed gases pass through line 94 and valve 95 to collection and separation in receiver 96. The condensate is removed from receiver 96 and directed through line 97 and valve 98 to storage or elsewhere, as desired. The gaseous products may be released from receiver 96 in the usual manner, by well known means not illustrated, or preferably, in case sub-atmospheric pressure is employed in chamber 80, they are directed from receiver 96 through line 99 to a vacuum pump, not illustrated, or preferably to some well known type of jet ejector such as indicated, for example, at 100, whereby sub-atmospheric pressure is maintained in receiver 96, condenser 93 and chamber 80. In the case here illustrated, steam is supplied through line 101 to ejector 100 and induces the flow of gases from receiver 96 through line 99 to condenser 102 wherein the steam is substantially condensed, to create a sub-atmospheric pressure in this zone, by introducing cold water through line 103 and valve 104 into direct contact therewith, the condensate being discharged from condensing chamber 102 through line 103 which has a suitable trap 105 at its lower end to prevent atmospheric air from entering chamber 102 and breaking the partial vacuum in this zone.

When relatively light refractory distillate is supplied to coil 76, as previously described, in addition to serving as a means of increasing velocity through the coil and decreasing the effective pressure in chamber 80, it serves as a blend-

ing agent for the condensate collected in receiver 96 and improves its fuel oil characteristics. By selecting a distillate for this purpose which does not have too low an initial boiling point and which, due to its refractory nature, will not undergo appreciable cracking in coil 76, and by regulating the amount of distillate so used, I am able to recover a condensate in receiver 96 meeting the requirements for premium fuel oil. I have found that selected light fractions of the intermediate liquid products formed in a conventional cracking operation, which fractions are commonly termed "pressure distillate bottoms" and have an approximate boiling range of 400 to 600° F., or thereabouts, are particularly suitable for the purpose and, further, that the quantity of such material necessary for blending with the condensate of the residuum cracking and reducing operation, to improve its fuel oil characteristics, will give the desired results with respect to velocity and partial pressure in coil 76 and chamber 80. A considerable variation in the amount of light distillate supplied to coil 76, so that this amount will correspond to that required for blending, is made possible without defeating its other purposes, by employing compensating variations in the firing conditions (and hence in the rates of heating) in furnace 71 and/or by varying the absolute pressure employed in chamber 80. For example, when a certain proportion of light distillate to flashed residue, in the mixture supplied to coil 76, is found to give a satisfactory degree of cracking for the flashed residue, under the specific temperature and pressure conditions employed, and the distillate collected in receiver 96 requires a greater quantity of light fractions to bring it to market specifications for premium fuel oil, the quantity of light distillate supplied to coil 76 may be correspondingly increased and, to compensate for this, somewhat higher rates of heating and a higher coil outlet temperature may be employed and/or the absolute pressure employed in chamber 80 may be increased. No set rules have been formulated for predetermining the exact temperature and pressure conditions and the exact proportions of flashed residue to light distillate in the mixture supplied to the flashed residue cracking and reducing step since these proportions will vary, depending upon the particular characteristics of the flashed residue being treated which, in turn, will depend upon the nature of the cracking stock from which they are derived and the conditions under which they are produced. However, for any given cracking stock and any given set of operating conditions, in that portion of the system preceding the flashed residue cracking and reducing steps, the proper operating conditions of the latter step may be empirically determined by starting the operation using an excess amount of light distillate supplied to coil 76, then gradually decreasing this amount until the characteristics of the condensate collected in receiver 96 are satisfactory and adjusting the temperature and pressure conditions in coil 76 and chamber 80 to correspond. I have found, for example, that with most cracked residues subjected to two stages of flash distillation, in the manner hereinbefore described, and with temperatures of the order of 850 to 950° F. at the outlet of coil 76 and with an absolute pressure in chamber 80 of the order of 50 mm. of mercury up to substantially atmospheric pressure, approximately 12 to 18% of substantially gas-free pressure distillate bottoms, based on the weight of the flashed residue supplied to coil 76, will give

the desired results with rates of heating, in that portion of coil 76 wherein the materials passing therethrough are at an active cracking temperature, of the order of 8,000 to 15,000 B. t. u.'s per hour, per square foot of external heating surface.

It is, of course, within the scope of the invention to supply light distillates, other than pressure distillate bottoms, to coil 76 for the purposes above mentioned. The only essential requirements of this material being that it is relatively low-boiling and readily vaporizable, will not be materially cracked under the conditions employed in the heating coil and will not contaminate the final fuel oil product or too greatly reduce its flash point. Other materials which are suitable for this purpose are, for example, straight-run or cracked naphtha, heavy gasoline fractions, light refractory gas oil and the like.

Provision is made for supplying either straight-run or cracked light distillate from storage or from a separate cracking system or elsewhere to coil 76 by means of line 118 and valve 119 communicating with coil 76 through lines 84 and 75.

The invention specifically contemplates the use of the secondary flashing step of the system and/or the flashed residue cracking and reducing step in conjunction with a plurality of conventional cracking units for reducing and converting the residual liquid produced within the latter. Provision is therefore made in the apparatus here illustrated for supplying residual liquid in heated state from one or a plurality of other cracking units, not illustrated, to chamber 37 by means of line 112 and valve 113 communicating with line 33. Provision is also made for introducing any heavy residual oil amenable to treatment, in the manner described, in coil 76, directly to the latter zone from the flash distilling step of a separate cracking system or from storage or elsewhere, as desired, through line 114 and valve 115. I have so provided for supplying a regulated portion or all of the oil removed from the lower portion of dephlegmator 40 to one or a plurality of cracking systems, other than that illustrated, through line 116 and valve 117.

The preferred range of operating conditions which may be employed in an apparatus such as illustrated and above described to accomplish the desired results are approximately as follows: A cracking temperature of the order of 850 to 950 F., or more, may be employed at the outlet of heating coil 1 with a superatmospheric pressure at this point in the system of the order of 100 to 350 pounds, or more, per square inch. Substantially the same or a somewhat lower pressure may be employed in reaction chamber 5 and the succeeding vaporizing and separating chamber 8 may be operated at a reduced superatmospheric pressure of the order of 50 to 150 pounds, or thereabouts, per square inch. The pressures employed in fractionator 11 and the succeeding condensing and collecting equipment will be substantially the same or lower than that employed in chamber 8. Secondary vaporizing and separating chamber 37 is operated at a lower pressure than that employed in chamber 8, the reduced pressure ranging, for example, from 50 pounds, or thereabouts, per square inch, superatmospheric, down to substantially atmospheric pressure. Fractionator 40, condenser 55 and receiver 58 are preferably operated at substantially the same pressure as that employed in chamber 37, although lower pressures may be utilized, when desired. The temperature employed at the

outlet of the flashed residue heating coil 76 may range, for example, from 775 to 950° F., or thereabouts, and the pressure employed at the outlet of this coil is preferably of the order of substantially atmospheric to 30 pounds, or thereabouts, per square inch, superatmospheric pressure. The pressure employed in chamber 80 may range from substantially atmospheric or a slight superatmospheric pressure down to a substantially atmospheric pressure corresponding to 50 mm. of mercury, or less, sub-atmospheric pressure being preferred in this zone. The pressure employed in chamber 80 may be substantially equalized in the succeeding condensing and collecting equipment.

As an example of one specific operation of the residue reducing and cracking steps of the process herein disclosed, a flashed liquid residue of approximately 17° A. P. I. is withdrawn from the vaporizing and separating chamber of a series-chamber type, multiple coil cracking system at a temperature of about 800° F. and supplied without intentional cooling to a secondary vaporizing and separating chamber operated at substantially atmospheric pressure. The flashed residual liquid is reduced in the secondary vaporizing and separating chamber to a gravity of approximately 0° A. P. I. and is directed therefrom at a temperature of approximately 700° F. to the residue heating coil. The vapors evolved in the secondary vaporizing and separating chamber are dephlegmated in contact with the charging stock for the process which is a heavy reduced crude of approximately 14.4° A. P. I. gravity. An overhead stream of dephlegmated vapors is removed from the upper portion of the dephlegmator at approximately 400° F. and subjected to condensation and cooling to form a distillate of about 35° A. P. I. gravity. This material amounts to about 22% by weight of the flashed residue supplied to the secondary vaporizing and separating chamber. A sufficient quantity of this material is returned to the upper portion of the secondary vaporizing and separating chamber to maintain a vapor outlet temperature from this zone of approximately 675° F. The remaining portion of this distillate is returned to the fractionator of the cracking system. The mixture of condensate and pre-heated charging stock formed in the dephlegmating step has a gravity of approximately 13 to 14° A. P. I. It is removed from the dephlegmator and supplied to the fractionator of the cracking system.

The quantity of secondary flashed residue produced is approximately 50% by weight of the flashed residue supplied to the secondary vaporizing and separating chamber and the additional cracking stock recovered therefrom in the form of distillate and condensate, returned, as above described, to the fractionator of the cracking system, amounts to approximately 50% by weight of the primary flashed residue. The quantity of charging stock supplied to the dephlegmator is approximately the same by weight as the quantity of primary flashed residue supplied to the secondary vaporizing and separating chamber. Therefore, in addition to the quantity of recycle stock produced in the conventional cracking operation with one stage of flash distillation, an additional quantity of cracking stock amounting to nearly 50% by weight of the raw oil charging stock is produced in the secondary flashing step.

The secondary flashed residue is blended prior

to its introduction into the residue heater with approximately 17% by weight of pressure distillate bottoms having a gravity of approximately 32° A. P. I. The resulting mixture is supplied to the residue heater at a temperature of approximately 610° F. and quickly heated therein to an outlet temperature of approximately 800° F. at substantially atmospheric pressure. The heated products are supplied to another vaporizing and separating chamber which is operated at an absolute pressure corresponding to approximately 55 mm. of mercury and are therein reduced to an asphaltic residue which has a softening point of approximately 300° F. and amount to approximately 50% by weight of the secondary flashed residue supplied to the residue heater or approximately 43% by weight of the mixture of secondary flashed residue and pressure distillate bottoms supplied to this heater. The vapors evolved in the last mentioned vaporizing and separating chamber are scrubbed to remove undesirable entrained and dissolved heavy asphaltic materials therefrom by continuously recycling to the upper portion of this zone a condensate removed from a somewhat lower point therein. This condensate having a gravity of approximately 6° A. P. I. is removed from the chamber at a temperature of approximately 750° F. and recycled without intentional cooling. The scrubbed vapors are withdrawn from the upper portion of the last mentioned vaporizing and separating chamber at a temperature of approximately 775° F. and are subjected to cooling and condensation to form a liquid product having a gravity of approximately 12 to 13° A. P. I. which amounts to over 60% by weight of the mixture of secondary flashed residue and pressure distillate bottoms supplied to the residue heater. This product meets market specifications for premium fuel oil and, after deducting therefrom an amount equivalent in weight to the total quantity of pressure distillate bottoms supplied to the residue heater, the remainder amounts to approximately 50% by weight of the secondary flashed residue supplied to the residue heater. The fuel oil condensate recovered as the final product of this residuum cracking and reducing process, although of heavier gravity than the flashed residue removed from the primary vaporizing and separating chamber of the conventional cracking system, is greatly superior to the latter in fuel oil characteristics and this product, together with the additional cracking stock recovered, as described, from a primary flashed residue, in the secondary vaporizing step, amounts to nearly 100% by weight of the latter, an exceptionally small amount of fixed gases and substantially no coke being produced.

I claim as my invention:

1. The method of converting hydrocarbon oils into more valuable products which comprises cracking the oil at cracking temperature and under superatmospheric pressure, flash distilling the resultant mixture of liquid and vaporous conversion products and separating the vapors from residual oil, fractionating and condensing said vapors, supplying said residual oil in heated state to a second flash distilling step wherein it is distilled by its contained heat and without appreciable cracking to a heavier residual liquid, condensing the vapors evolved by said second flash distillation and supplying resulting condensate to the cracking step, removing said heavy residual liquid from the second flash distilling step, commingling regulated minor quantities of relatively

light distillate therewith, quickly heating the mixture to a temperature adequate to effect substantially complete vaporization of said distillate and to effect mild cracking of said heavier liquid residue, removing the resulting heated products from the heating zone without permitting them to remain therein for a sufficient length of time to cause deleterious secondary cracking reactions, supplying said heated products to a separate zone of low pressure vaporization and therein reducing the same, without additional heating and without substantial continued cracking, to a semi-solid residue, removing said semi-solid residue in heated fluid state from said low pressure zone, and condensing vapors evolved in the residue heating and low pressure vaporizing step to form a condensate.

2. The process defined in claim 1, wherein said vaporizing zone, to which the heated products of the residue cracking step is supplied, is operated at sub-atmospheric pressure.

3. The process defined in claim 1, further characterized in that the yield of the last named condensate, after deducting therefrom an amount equivalent to the weight of said light distillate supplied to the residue heating step, amounts to at least 50 per cent by weight of said heavier liquid residue supplied to the residue heating step.

4. The process defined in claim 1, wherein the character of said light distillate supplied to the residue heating step is such that no substantial cracking thereof occurs and wherein the quantity of said distillate employed is regulated to produce, as the last named condensate, a product meeting market specifications for premium fuel oil.

5. The process of pyrolytically converting hydrocarbon oils to produce therefrom high yields of good antiknock gasoline with minor yields of semi-solid residue and a heavy liquid product suitable as fuel oil, with no substantial coke production, which comprises cracking hydrocarbon oil at cracking temperature and substantial superatmospheric pressure, flash distilling the resulting liquid conversion products in commingled state with the vaporous products of the cracking operation to form additional vapors and residual liquid, fractionating the vapors resulting from said cracking and flash distillation to form reflux condensate and fractionated vapors of the desired end-boiling point, condensing said fractionated vapors to form the light distillate product of the process comprising said gasoline, removing said residual liquid in heated state from the flash distilling zone and further flash distilling the same, without additional heating, to form a heavier liquid residue and substantial quantities of additional vapors, substantially condensing vapors evolved in the last name flash distilling step and returning resulting condensate to the cracking operation for further cracking treatment, removing said heavier liquid residue from the second named flash distilling step, commingling therewith regulated minor quantities of said reflux condensate, quickly heating the mixture to a temperature adequate to substantially completely vaporize said reflux condensate and mildly crack said heavier liquid residue, removing the resulting heated products from the heating zone without allowing them to remain therein for a sufficient length of time to cause detrimental secondary cracking reactions, discharging said heated products into a separate low pressure zone and therein reducing the same by extensive

vaporization without additional heating and without intentional cooling to said semi-solid residue, removing the latter in heated fluid state from said low pressure zone, separately removing vapors evolved from said heated products in the low pressure zone therefrom, and condensing the same to form said fuel oil product.

6. The process defined in claim 5, wherein oil resulting from said condensation of the vapors evolved in the second named flash distilling step is returned to the first mentioned fractionating step.

7. The process defined in claim 5, wherein vapors evolved in the second mentioned flash distilling step are dephlegmated to form relatively light vapors and relatively heavy condensate, the latter being returned to the cracking operation for further cracking treatment and said lower boiling dephlegmated vapors being separately condensed to form distillate which is returned, in part, to the second named flash distilling step as a cooling and refluxing medium and, in part, to the first mentioned fractionating step.

8. A conversion process which comprises subjecting hydrocarbon oil to cracking conditions of temperature and pressure and flash distilling the resultant products to separate the same into vapors and unvaporized oil, fractionating the vapors to form relatively heavy and light reflux condensates, further flashing the unvaporized oil to reduce the same to a heavy residual liquid, condensing the vapors evolved by said further 10 flashing and returning resultant condensate to the cracking step, combining said heavy residual liquid with light reflux condensate formed by the fractionation, heating the resultant mixture in a heating coil sufficiently to vaporize said light 15 condensate and mildly crack the residual liquid, discharging the heated mixture into a low pressure vaporizing zone and therein separating the same into vapors and residue independently of the products of the first-mentioned cracking 20 step, and condensing and collecting the last-mentioned vapors.
